UNITED STATES PATENT OFFICE.

ELMER M. PRATT AND ALBERT H. ROCKEFELLER, OF MACKSVILLE, KANSAS; SAID PRATT ASSIGNOR TO SAID ROCKEFELLER.

PORTABLE NEST STRUCTURE.

1,350,264.

Specification of Letters Patent. Patented Aug. 17, 1920.

Application filed June 25, 1919. Serial No. 306,710.

To all whom it may concern:

Be it known that we, ELMER M. PRATT and ALBERT H. ROCKEFELLER, citizens of the United States, residing at Macksville, 5 in the county of Stafford and State of Kansas, have invented certain new and useful Improvements in Portable Nest Structures, of which the following is a specification.

The invention relates to a portable nest 10 structure, and more particularly to the class of grouped hens' nests arranged in stairstep order in rows.

The primary object of the invention is the provision of a nest structure of this 15 character, wherein the compartments are grouped in rows arranged in step by step fashion and the grouped nests are supported upon legs so that the same can be positioned outside of a hen house and are elevated to 20 permit the chickens to pass beneath the nests, each compartment being rendered lice and mice proof and being readily cleanable to make the same sanitary.

Another object of the invention is the provision of a nest structure, of this character, 25 wherein a multiplicity of compartments forming independent nests can be grouped together, yet retaining the individual character of the respective nests, the structure being of novel form to assure ready and 30 easy accessibility, whereby eggs can be gathered therefrom with despatch, and also which is readily portable.

A further object of the invention is the provision of a nest structure of this character, which is extremely simple in construction, strong, durable, and inexpensive to manufacture.

With these and other objects in view, the 40 invention consists of the features of construction, combination and arrangement of parts as will be hereinafter fully described, illustrated in the accompanying drawings, and pointed out in the claim hereunto appended.

In the accompanying drawings:

Figure 1 is a perspective view of a nest structure constructed in accordance with the invention,

50 Fig. 2 is a vertical sectional elevation,
Fig. 3 is a rear elevation,

Fig. 4 is a sectional view on the line 4-4 of Fig. 3.

Similar reference characters indicate cor-

responding parts throughout the several 55 views in the drawings.

Referring to the drawings in detail, A designates the lower body and B the upper body of superposed rows of hens' nests, each body being made from galvanized sheet 60 metal and comprising a back 5 formed with the ends 6 and top 7, the latter being provided with rightangular depending flanges 8 to which are riveted the ends 6. It will be apparent that the bottom and front of 65 the bodies A and B are open and these bodies are held in superposed relation to each other simulating stairstep fashion in a manner presently described.

The bodies A and B at their ends 6 have 70 secured thereto horizontal end pieces 9 to which are fastened the vertically disposed front and rear legs 10 and 11 respectively, the legs being also fastened to the ends 6 of said body and in this manner said legs are 75 a unitary part and will support the bodies A and B elevated a distance from a foundation or ground.

Located within each body A and B is a series of vertical partitions 12 formed with 80 rightangular flanges 13 at the top and rear edges, these flanges being riveted or otherwise fastened to the back 5 and the top 7 so that the partitions 12 are fast within the body and the same are arranged in spaced 85 relation to each other for dividing the body into a plurality of independent compartments 14 forming the individual nests therein. Each partition 12 in the body A has formed at its edge a rightangular ear 15 to 90 which is fastened a front strip 16 extending longitudinally of the body contiguous to the open bottom thereof. Hinged to this strip 16 as at 17 is a swinging bottom 18 which when in closed position closes the open bottom of the body. Mounted on the back 5 of each body is a pair of spring catches 19 for engaging the swinging bottom 18 to hold the same in closed position.

Secured to the front strip 16 on the lower 100 body A at the ends thereof are pivot brackets 20 to which are pivotally connected strap hinges 21 having fixed thereto a running board 22, the brackets 20 being formed with stops 23 for holding the running board 105 22 when in lowered horizontal position. The running board 22 on its upper face has suitably secured thereto a rubberoid mat

24, the board 22 being reinforced transversely through the medium of angle irons 25 which are secured to the under face thereof.

5 Carried by the back 5 of the lower body A is a spacer strip 26 having bends 26' for engaging the front edges of the vertical partitions 12 located within the upper body B. The upper body B is devoid of front strip 16 for the reason that the back 5 of the lower body A extends a slight distance upwardly over the open front of said body B and the bottom 18 for the upper body B is hinged directly to the back 5 of the lower body A.

It will be clearly obvious that the compartments 14 in the bodies A and B can be readily cleaned so as to render the same sanitary and also that these compartments 20 are accessible for the gathering of eggs therefrom. The nest structure is readily portable so that the same can be placed at any desirable location outside of the hen house and the nests in their elevated position will be mice proof. It is obvious that the nest structure does not occupy any floor space and by the reason of the elevated position thereof will permit the chickens to pass underneath of the same. It is of course 25 to be understood that any number of compartments 14 can be arranged in the bodies A and B to increase the capacity of the nest structure.

From the foregoing it is thought that the construction and the manner of operation of the nest structure will be clearly understood and therefore a more extended explanation has been omitted.

What is claimed is:

A portable nest structure of the character 40 described comprising superposed bodies, one being arranged forwardly of the other in a step by step fashion, each body being formed from sheet metal having an open front and bottom, a support for the bodies 45 having angle irons forming corner legs, partitions arranged within each body for dividing the same into independent compartments, a front strip secured to the lowermost body at its open front, ears formed on 50 the partitions in the lowermost body and fastened to the front strip, a spacer strip located between the bodies and having bends for engaging the partitions in the uppermost body, a running board swingingly supported on the front strip and adapted to be moved to a position for closing the lowermost body and also to be moved to another position to lie in a horizontal plane, a door section hinged to each body at its bottom, 55 and means for latching the door sections closed.

In testimony whereof we affix our signatures hereto.

ELMER M. PRATT.
ALBERT H. ROCKEFELLER.
